DOMESTIC APPLIANCE

Donald K. Ferris, Dayton, Ohio, assignor to General Motors Corporation, Dayton, Ohio, a corporation of Delaware

Application May 14, 1943, Serial No. 486,932

4 Claims. (Cl. 34—82)

1

This invention relates to domestic appliance, and more particularly to a clothes drier.

An object of this invention is to provide a clothes drier in which a source of radiant heat rays, such as infra-red rays, is provided, together with means for focusing said rays into the main body of tumbling clothes in order to dry the clothes.

Another object of this invention is to provide a clothes drier in which a source of radiant heat rays is provided, together with a stream of air, and with a means for tumbling clothes, in the path of the stream of air.

Further objects and advantages of the present invention will be apparent from the following description, reference being had to the accompanying drawings, wherein a preferred form of the present invention is clearly shown.

In the drawings:

Fig. 1 is a side elevation of a clothes drier, with one side of the casing removed;

Fig. 2 is a vertical cross-sectional view of the clothes drier taken substantially along the line 2—2 of Fig. 4;

Fig. 3 is a vertical cross-sectional view taken along the line 3—3 of Fig. 1; and

Fig. 4 is a vertical cross-sectional view taken along the line 4—4 of Fig. 2.

A clothes drier according to this invention is provided with a source of radiant heat rays, which are directed against the clothes to be dried. These clothes are tumbled in front of the rays and air is circulated past the clothes. By this construction substantially all of the heat energy is directed on the clothes themselves, and it is not necessary to heat a large amount of air or a bulky apparatus in order to dry the clothes.

In a preferred form of the invention, a source of radiant heat rays, which preferably takes the form of one or more infra-red lamps 10, is mounted to emanate radiant heat rays, such as infra-red, into an insulated case 11. Means are provided for maintaining the main body of tumbling clothes in the path of such rays, such as a rotatable drum 12, mounted to rotate in the casing 11. This drum allows the infra-red rays to pass into the drum and into the main body of clothes, and may be made of some foraminous material such as wire mesh. The drum may be provided with a plurality of baffles 13 for tumbling clothes placed in the drum. If desired, the baffles 13 may be made by indentations of the wire mesh cloth, as indicated in the drawings or may be of any other desired form.

Means are provided for blowing a stream of

2

air past the tumbling clothes. Such means may take the form of a blower 14, which draws air into the louvers 15, past the blower 14 into the duct 16, past the inlet 16a from whence the stream flows into and around the drum 12, past the tumbling clothes therein. From thence the air may circulate past the casing outlet 17a into the duct 17 and out through the duct outlets 18 and 19.

10 Preferably the air stream is introduced into the casing 11 near the top at the inlet 16a and is removed near the bottom of the casing 11 at the outlet 17a. By this construction the air which has been slightly heated by the lamps 10 and 15 which tends to rise by convection to the top of casing 11 is entrapped by the forced air stream at 16a and is carried past the tumbling clothes into the outlet 17a. This slightly heated air, together with the large amount of heat introduced 20 directly into the clothes by radiation, quickly dries the clothes.

The duct outlet 18 may be provided with a removable screen 20. The screen 20 acts as a lint trap, which prevents lint from flying into the room in which the drier is located. Should the screen 20 become over-clogged, the stream of air is free to make a sharp upward turn and to flow out of the unscreened outlet 19.

Means are provided for ozonizing the stream 30 of air before it comes in contact with the tumbling clothes. For this purpose an ozonizer, diagrammatically indicated at 21, may be provided in the stream of air, such as in the duct 16, to 35 ozonize the air before it comes in contact with the tumbling clothes. This causes some bleaching action on the clothes and imparts a fresh "outdoor" odor to the clothes.

An electric motor 22 is provided, which is drivingly connected to the blower 14 and to the drum 40 12. If desired, the motor 22 may be provided with a pulley 23, which is connected to the speed reducing pulley construction 24, terminating in the pulley 25 drivingly connected to the drum 12 through the medium of a shaft 26 mounted in a bearing 27.

The insulated casing 11 is provided with a hinged door 28. A casing 29 may surround the insulated casing 11, except at the door 28.

The drum 12 may be provided with an opening 50 30 in its end wall, which registers with the door 28, so that clothes may be inserted or withdrawn from the drum 12.

Proper controls for the drier are provided. The switch controller 31 is mounted at any convenient 55 location and is provided with a control handle

32. The control handle 32 controls switch structures which connect the source of electrical power 33 with the lamps 10, the ozonizer 21 and motor 22. If desired, the single handle 32 may be connected to switch arrangement so that the lamps, ozonizer and motor are simultaneously energized and deenergized. Individual switches 31a may be provided to disconnect the lamps 10, ozonizer 21 or motor 22 selectively.

If desired, an automatic control may be provided for stopping operation of the machine when the clothes have been sufficiently dried. For this purpose a sensitive device 34 may be placed in the stream of air after it has passed in contact with the clothes. This device 34 may be made sensitive to a condition of the stream of air, such as humidity and/or temperature. It may be connected with the switching arrangement in structure 31 to trip a snap-acting device when the temperature or humidity of the air is of the character which comes from hot dry clothes. When the clothes have been sufficiently dried, the humidity of the air is substantially reduced. Also, when the clothes have been sufficiently dried, the temperature of the air rises rapidly. The device 34 may be made responsive to either or both the temperature or humidity of the air to actuate the trip device in the switch structure 31 to stop operation of the machine. The switch structure per se is obvious to those skilled in the art, and therefore details thereof are not shown.

The lamps 10 preferably are of the type in which the electric heater is enclosed in glass or other ray transparent medium, so that no lint can accidentally come in contact with the glowing resistance. By way of example, the lamps 10 may be mounted in front of a gold plated reflector 10b so curved as to focus the rays into the clothes at 10c. The lamps have heater 10d encased in glass 10e. The drum 12 is rotated in the direction shown by the arrows, so that the main body of clothes is in front of the heaters and within the focal length of the reflector. The clothes may be brought close to the heaters because there is no fire hazard when the heaters are protected by glass or other transparent medium. Any form of infra-red ray source may be used in which the heater is protected by special glass or any other medium transparent to infra-red rays. If desired the resistances may be mounted in a bank behind a single pane of glass and in front of the reflector.

The lamps 10 are preferably removable, such as by being mounted on the removable base 10a for replacement or repairs.

55

Merely by way of example, with a drum 24 inches in diameter and 18 inches long, a bank of six infra-red lamps may be used, with a total power consumption of 1500 watts. Such a structure has a drying capacity substantially equal to a drying device having the same size drum and consuming a much higher current and which does not apply the heat according to my invention.

10 While the form of embodiment of the invention as herein disclosed, constitutes a preferred form, it is to be understood that other forms might be adopted, as may come within the scope of the claims which follow.

What is claimed is as follows:

15 1. A clothes drier comprising a stationary casing, a perforated, cylindrical, drum in said casing rotatable about a horizontal axis, means for rotating said drum about said axis, an infra-red lamp comprising an infra-red electric heater encased in glass supported in said casing adjacent the lower upwardly rising portion of said drum, and means to circulate air through said casing and drum.

25 2. A clothes drier comprising a stationary casing, a perforated, cylindrical, drum in said casing rotatable about a horizontal axis, means for rotating said drum about said axis, a plurality of lamps each comprising an infra-red electric heater encased in glass supported in said casing 30 outside said drum adjacent the lower, upwardly rising portion of said drum, said lamps constituting the main heating means of said drier, and means to circulate air through said casing and drum.

35 3. A clothes drier comprising a stationary casing, a perforated, cylindrical, drum in said casing rotatable about a horizontal axis, baffles in said drum, means for rotating said drum about said axis, a plurality of lamps each comprising an infra-red electric heater encased in glass supported in said casing 40 outside said drum adjacent the lower, upwardly rising portion of said drum, said lamps constituting the main heating means of said drier and means to circulate air through said casing and drum.

45 4. A clothes drier comprising a stationary casing, a rotatable clothes drying support in said casing, heating means in said casing, means to blow air into said casing, and means forming an outlet for air from said casing including a duct having a lint arresting screen, and another duct at an angle to said first named duct connected adjacent said screen at a place reached by the air before it reaches said screen.

DONALD K. FERRIS.

Disclaimer

2,406,494.—Donald K. Ferris, Dayton, Ohio. DOMESTIC APPLIANCE. Patent dated Aug. 27, 1946. Disclaimer filed Sept. 29, 1948, by the inventor; the assignee, General Motors Corporation, consenting and affirming.

Hereby enters this disclaimer to claim 4 of said patent.
